UNITED STATES PATENT OFFICE.

DAYTON A. MINARD, OF BUFFALO, NEW YORK.

DESIGN FOR A FAN.

SPECIFICATION forming part of Design No. 30,924, dated May 30, 1899.

Application filed April 28, 1899. Serial No. 714,619. Term of patent 3½ years.

To all whom it may concern:

Be it known that I, DAYTON A. MINARD, a citizen of the United States, residing at Buffalo, in the county of Erie and State of New York, have invented and produced a new and original Design for Fans, of which the following is a specification, reference being had to the accompanying drawings, showing a part thereof.

10 In the drawings, Figure 1 shows a face view of a fan arranged according to my design, and Fig. 2 is an edge view of the same.

Referring to the drawings, the general outline of my design is that of a frying-pan, the body 1 of the fan representing the body of the pan, and the handle 2 of the fan representing the handle of the frying-pan. In the handle of the fan is cut a small orifice 3, as seen in the drawings. The body of the pan is shown as 15 circular, with a short spout 4 on its left-hand side, (see Fig. 1,) and the handle of the fan

is of greater thickness than its body portion, as shown in Fig. 2, the body portion of the fan being prolonged on the same plane as the handle, the general outline of the fan being also that of the frying-pan and its surface or further illustration of the frying-pan being carried out by printing in surface lines and shading.

Having thus described my design, what I claim, and desire to secure by Letters Patent, is—

The design for a fan as herein shown and described.

In testimony whereof I have signed my name to this specification in the presence of two subscribing witnesses.

DAYTON A. MINARD.
